(57) **CLAIM**

The ornamental design for a transition section for a turbocharged engine, as shown and described.

DESCRIPTION

FIG. 1 is a bottom back perspective view of a design for a transition section for a turbocharged engine according to the present disclosure.

FIG. 2 is top back perspective view of the transition section for a turbocharged engine of FIG. 1.

FIG. 3 is a front view of the transition section for a turbocharged engine of FIG. 1.

FIG. 4 is a back view of the transition section for a turbocharged engine of FIG. 1.

FIG. 5 is a left side view of the transition section for a turbocharged engine of FIG. 1.

FIG. 6 is a right side view of the transition section for a turbocharged engine of FIG. 1.

FIG. 7 is a top view of the transition section for a turbocharged engine of FIG. 1; and,

FIG. 8 is bottom view of the transition section for a turbocharged engine of FIG. 1.

The transition section may be in an engine exhaust system. The dash-dot-dash lines shown by FIGS. 1, 2, 7, and 8 define the bounds of the claimed design and form no part thereof.

1 Claim, 8 Drawing Sheets
